Primary Examiner—Susan J. Lucas*Attorney, Agent, or Firm*—Samuel Meerkreebs[57] **CLAIM**

The ornamental design for luminaire, as shown and described.

DESCRIPTION

FIGS. 1, 2 and 3 are front perspective views of the luminaire showing my new design;

FIG. 4 is a front elevational view thereof;

FIG. 5 is a rear elevational view thereof;

FIG. 6 is a top plan view thereof, the opposite view being a mirror image;

FIG. 7 is a left side elevational view thereof;

FIG. 8 is a right side elevational view thereof;

FIG. 9 is a rear perspective view thereof;

FIGS. 10 and 11 are front perspective views of another embodiment showing my new design;

FIG. 12 is a front elevational view thereof;

FIG. 13 is a rear elevational view thereof;

FIG. 14 is a top plan view thereof, the opposite view being a mirror image;

FIG. 15 is a left side elevational view thereof;

FIG. 16 is a right side elevational view thereof;

FIG. 17 is a rear perspective view thereof;

FIGS. 18, 19, 20 and 21 are front perspective views of another embodiment showing my new design;

FIG. 22 is a front elevational view thereof;

FIG. 23 is a rear elevational view thereof;

FIG. 24 is a top plan view thereof;

FIG. 25 is a bottom plan view thereof;

FIG. 26 is left side elevational view thereof;

FIG. 27 is a right side elevational view thereof; and,

FIGS. 28 and 29 are rear perspective views thereof.
